UNITED STATES PATENT OFFICE.

GEORGE W. PACKER, OF ROCK FALLS, ILLINOIS.

CHECK-ROWER.

SPECIFICATION forming part of Letters Patent No. 321,449, dated July 7, 1885.

Application filed January 5, 1885. (No model.)

To all whom it may concern:

Be it known that I, GEORGE W. PACKER, a citizen of the United States, residing at Rock Falls, in the county of Whiteside and State of Illinois, have invented certain new and useful Improvements in Check-Rowers; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

My invention has reference to check-rowers, and pertains to certain novel mechanism for transmitting to the seeding devices the action of the forks when the latter are actuated by the knotted cord or wire stretched across the field, including a novel method of reciprocating the pitman attached to the transverse bar, which extends from one seed-hopper to the other.

As my invention is attached in the usual way to any of the ordinary two-horse planters, the constructions of which are well known, I do not deem it essential to show or describe any portion of such planters.

In the drawings, Figure 1 is a top plan view of a machine embodying my invention. Fig. 2 is a rear elevation of the central portion of the same. Fig. 3 is an end elevation of the same. Fig. 4 is a rear elevation of the central ratchet with a portion of the cap H and cross-beam A removed. Fig. 5 shows the top of the ratchet G with the top of the cap H removed, the channels L under such ratchet being shown in dotted lines. Fig. 6 shows the bottom of the ratchet G with the pitman P at the limit of its outstroke. Fig. 7 exhibits the same with such pitman at the limit of its in-stroke. Fig. 8 is a detailed view of such pitman and the pivoted travelers M and N which actuate it.

A is the usual cross-beam attached in any suitable way transversely of the planter at the seed-hoppers.

B is the usual knotted cord carried in the usual way on the guide-pulleys a.

C is a fork journaled vertically at the end of the beam A in such relation to the cord B as to be engaged and actuated by the knots

thereon. The fork C is interiorly provided at its lower end with the segmental bevel-gear c.

D is a bell-crank lever pivoted horizontally at its angle on the beam A, and provided exteriorly with the segmental bevel-gear d, which engages and is actuated by the bevel-gear c on the fork C, such lever D having its oscillations transversely of the machine.

E is a draw-rod pivoted at its outer end to the inner arm of the lever D, and connected at its inner end to the inner end of the coiled spring F, which latter is adjustably attached at its outer end to the beam A by means of a slotted plate; f.

G is a ratchet (Fig. 4) pivoted horizontally by means of a screw, e, passed downward through the center of the stationary cap H, which incloses such ratchet. A hollow vertical boss, h, is formed on the center of the top of the cap H. The screw e is screwed into a corresponding thread formed in the center of the upper portion of the ratchet G, and the screw e, having its head resting on the top of the boss h, revolves with the ratchet G. In the upper surface of the ratchet G and extending to its periphery are formed the four equidistant notches g, each of which has one vertical end, and its lower surface sloping thence upward to the vertical end of the succeeding notch g. The rod E is provided with the downwardly-projected rigid vertical pawl i, fixed in such locality on the rod E as at the limit of the instroke of the latter it will engage one of the notches g, and drawing against the vertical end of the latter will, in its out-stroke, impart to the ratchet G a quarter-revolution. At this instant the fork C will be released from the knot on the cord B, and the spring F, through the medium of the rod E, lever D, and bevel-gears c and d, will throw the fork C forward in position to be actuated by the next succeeding knot on the cord B. The action last described will also draw the pawl i up the inclined bottom of the notch g and drop it into the next succeeding notch g in position to give another impulse or quarter-revolution to the ratchet G when the fork C shall be next actuated by the cord B.

It will be observed that the outer or fixed end of the spring F is lower than the end of such spring attached to the rod E, and there-

fore the reaction of such spring is in a downward direction, and secures the successive engagement of its pawl *i* in the notches *g*. The inner end of the rod *E*, with which the pawl *i* is integral, is screwed onto the residue of the rod, and by means of a thread on the latter the length of the rod can be altered, and the pawls *i* adjusted to act to and from the proper points on the ratchet *G*.

10 The machine is of course in duplicate, so as to operate from each end alternately, and in the action from one end just described the other actuating parts are at rest, except that the other pawl *i* in the quarter-revolution of 15 the ratchet *G* described, passes up the inclined bottom of the opposite notch *g*, or rather the ratchet moves under the second or stationary pawl *i*, and at the instant that the actuating-pawl *i* has ceased its draft such stationary pawl drops into the deepest portion 20 of its next succeeding notch *g*, and thereby forms a lock to hold the ratchet *G* stationary while the actuating-pawl *i* is drawn inward and up the inclined bottom of its notch *g* to 25 engagement with its next succeeding notch *g*. Thus the ratchet *G* is prevented from having any backward revolution while the actuating-pawl *i* is, by its spring *F*, drawn inward to engage its next succeeding notch *g*. Curved 30 grooves *h*' in the top of the cap *H*, through which the pawls *i* downwardly project, furnish guides, respectively, for the latter.

In the lower surface of the ratchet *G* are formed the two grooves or channels *L*, which 35 extend at right angles to each other across such lower face. Such grooves are so located in reference to the notches *g* as to have their respective ends projected midway between such notches, as will be seen in Fig. 5, wherein 40 the position of such grooves relative to such notches is exhibited in dotted lines.

M and *N* are travelers pivoted, as shown, on the upper surface of the pitman *P*, which latter is suitably connected at its outer end to 45 the usual transverse reciprocating bar, which connects and operates the seeding devices. The length of stroke can be gaged by changing the relative distance between the travelers *M* and *N*, or by interposing a short lever between 50 such pitman and the reciprocating bar.

In the aforesaid rotation of the ratchet *G* the pitman *P* and travelers *M* and *N* assume the positions shown in Figs. 6 and 7, changing alternately from one of such positions to the 55 other at each quarter-revolution of the ratchet *G*. It will be seen that this movement causes the pitman *P* to alternately approach to and recede from the center of such ratchet *G* the distance between the pivotal points of the 60 travelers *M* and *N* at each quarter-revolution of such ratchet. Thus at each entire revolution of such ratchet there are four movements of the pitman *P* and four actions of the seeding devices. In other words, the pitman *P* 65 and seeding devices are actuated at each quarter-revolution of the ratchet *G*, whereas in the usual mode of pivoting the pitman at one point

on the ratchet a half-revolution of the latter is requisite to impart a full stroke to such pitman. As a short, quick stroke in dropping 70 the seed is necessary, this feature of my invention is of great importance. A circular plate, *R*, Fig. 4, rests on the beam *A* and fits into the bottom of the cap *H*, thus excluding the dust from the parts and furnishing a smooth 75 base for the movement of the inner end of the pitman *P*. A horizontal slot, *l*, is cut in the side of the cap *H* to admit the inner end of the pitman *P*.

There are numerous advantages in my invention. It permits the use of a vertical fork, which is superior to a horizontal one. By locating the ratchet between the spring *F* and fork *C*, the rod *E* is drawn alternately from each end, and therefore a lighter rod is sufficient and the action thereof more certain than where both fork and spring are at the outer end of such rod. By the use of the bevel-gear the effect of actuating the fork is made instantaneous and certain. By locating the springs as 80 shown I am enabled to use the one not connected with the actuating-pawl to force the stationary pawl into the notches *g*, and thereby form a lock of the ratchet *G* during the interval that the latter is stationary. By the connection shown of 85 the pitman *P* to the ratchet *G*, I am enabled to give such pitman an impulse sufficient to actuate the seed devices at each quarter-revolution of such ratchet and to stop the pitman after such action on the dead-point, so that it 90 will of itself remain stationary until again acted upon. The direction of the revolution of the ratchet *G* is indicated by the arrows and numeral 1 in Figs. 6 and 7. The travelers *M* and *N* traverse, in the rotation of the ratchets, 95 the respective grooves in which they are shown, each moving from the center outward and then inward in its particular groove at each quarter-revolution of such ratchet, and each alternately passing into the respective ends of its 100 groove.

I am aware that forked vertical arms provided with segmental gear have been used to oscillate corresponding gear seated on a rock-shaft; but this construction is objectionable in 115 requiring the exercise of greater power, through such arm, to overcome the inertia of such shaft, and also in requiring a stiff spring to return such shaft, and, usually, ratchet mechanism to control such shaft, besides making the 120 machine unnecessarily complex and expensive. My invention in this behalf consists in a construction which dispenses entirely with a rock-shaft and its adjunctive mechanism by meshing the gear of the actuating-arm into a second 125 gear and attaching the draw-rod directly to such second gear. This, I believe, has never previously been done in a construction embodying a vertical arm or fork.

What I claim as my invention, and desire to 130 secure by Letters Patent of the United States, is—

1. The combination of the vertical arm or fork *C*, provided with gear *c* on its shank, the

geared lever D, and the actuating-rod E, connected directly to such last-named gear, substantially as shown, whereby the interposition of the usual rock-shaft is avoided, and the parts 5 employed are fewer, simpler, and more easily operated, while the advantages of a vertical arm are retained.

2. The combination of the vertical fork C, provided with the gear c, the lever D, provided with the gear d, the rod E, the spring F, the pawl i, and the ratchet G, provided with notches g, substantially as shown, and for the purpose specified.

3. The combination of the vertical fork C, provided with the gear c, the lever D, provided with the gear d, the rod E, the spring F, the pawl i, and the ratchet G, provided with the notches g, such ratchet being located between such spring and fork, substantially as 20 shown, and for the purpose specified.

4. The combination of the fork C, provided with the gear c, the lever D, provided with the gear d, rod E, provided with the pawl i, spring F, ratchet G, provided with notches g, second 25 rod, E, having pawl i, and the second spring, F, whereby the ratchet G is alternately actuated and locked, substantially as shown, and for the purpose described.

5. The combination of the ratchet G, provided with the grooves L, the pitman P, and the travelers M and N, substantially as shown, and for the purpose mentioned.

6. The combination of the ratchet G, pro-

vided with grooves L, and the pitman P, provided with the travelers M and N, substantially 35 as shown.

7. The combination of the pivoted ratchet G, provided with the grooves L, suitable actuating-pawl or their equivalent, the pitman P, and travelers M and N, substantially as shown, 40 and for the purpose described.

8. The ratchet G, provided with the notches g, and grooves L, the latter being, respectively, on a line midway of such notches, substantially as shown.

9. The combination of the cap H, provided with slots h', the ratchet G, provided with four equidistant notches, g, the screw e, and pawl i, whereby such pawl is guided in its operations, and each outward motion thereof imparts a 50 quarter-revolution to such ratchet, substantially as shown, and for the purpose described.

10. The combination of an actuating-fork, a reacting spring, intermediate actuating mechanism, and a ratchet located between such fork and spring, whereby the alternate action of such fork and spring shall be from such ratchet, substantially as shown, and for the purpose described.

In testimony whereof I affix my signature in 60 presence of two witnesses.
